(57) **CLAIM**

The ornamental design for a pair of corn cob holders, as shown and described.

DESCRIPTION

FIG. 1 is a perspective view of a pair of corn cob holders.

FIG. 2 is another perspective view of the pair of corn cob holders of FIG. 1.

FIG. 3 is a side view of the pair of corn cob holders of FIG. 1.

FIG. 4 is another side view of the pair of corn cob holders of FIG. 1.

FIG. 5 is a top view of the pair of corn cob holders of FIG. 1; and,

FIG. 6 is a bottom view of the pair of corn cob holders of FIG. 1.

The surface shading illustrated in the drawings is provided merely to highlight the contour of design; it is not intended to be illustrative of texture or gloss.

The broken lines showing the corn cob are for illustrative purposes only and form no part of the claimed design.
